UNITED STATES PATENT OFFICE

AUGUSTE LOUIS RICORDEL, OF PARIS, FRANCE, ASSIGNOR TO PRECISION MODERNE,
OF PARIS, FRANCE, A CORPORATION OF FRANCE

FIRING-DEVICE FOR DEMOUNTABLE MACHINE-GUNS

Application filed November 30, 1931, Serial No. 578,096, and in France December 3, 1930.

The present invention relates to improvements in mounting for machine-guns, particularly those for firing at aerial objects, such as are described in U. S. Patent 5 1,722,862.

These improvements are concerned with the firing mechanism for demountable machine-guns and are directed in the first place to enabling this to be used by persons of different heights without the necessity each time of making a fresh adjustment and in the second place to ensure safety in the firing by preventing the insertion of projectiles into the gun if the firing pedal of the 10 mounting is accidentally depressed in firing 15 position.

A further improvement facilitates the demounting of the mounting by facilitating the lifting of the head of the mounting so 20 as to remove it from the grid support.

Figure 1 is a side-elevation and Figure 2 is a plan of the mounting showing the improvements in the firing mechanism.

Figure 3 is a detail view illustrative of the 25 end of the support of the feet pedal of the firing mechanism, viewed in a direction perpendicular to that of Figure 1.

Figure 4 is an axial sectional elevation of the machine-gun showing the parts assembled.

The firing is effected by means of pedal 141 mounted on a support 142 or on the support for the foot-rests.

According to the present invention, the 30 foot rest 143 can be displaced as well as the axis 144 of the pedal, to which it is secured, without having to alter the adjustment of the firing mechanism. For this purpose, the axis 144 of the pedal carries a 35 lever 145 which acts on a lever 146 which can slide along a square rod 147, which 40 itself can rotate in the foot rest. By means of a lever 148, lever 149, link 151, the movement is transmitted to the cam 153 which 45 acts on the lever 154 of the firing mechanism. The slide which carries the foot rest 143 and 50 the axis 114 of the pedal is displaced along the support 142 by means of the screw 153 (see particularly Figure 2) controlled by the knurled knob 156.

The mounting according to the present invention includes inter alia means for preventing loading of the mitrailleuse when the pedal 141 is depressed.

This means comprises a lever 158 rotatable 55 about an axis 159 and capable of movement into position in front of the loading channel 161 (dotted position). The other end of this lever is connected to the firing lever 154 by the link 162 sliding in the 60 socket 163, a spring 164 being inserted between the link and the socket so as to urge the one towards the other.

When the parts are in the position shown in the figure (pedal 141 raised and charging 65 mechanism open), it will be seen that the lever 158 does not engage the channel so that the mitrailleuse can be loaded.

When, on the other hand, the pedal 141 is depressed (with the parts as shown by the 70 dotted lines), the lever 158 prevents access to the channel.

When the cartridge is in position and the 75 pedal 141 is depressed, the lever 158 presses on the cartridge which is in the channel and the cam 153 can act on the firing lever 154 owing to the extensibility of the system 162, 163 permitted by the spring 164.

Finally (Figure 4) in order to secure the 80 head 109 on the guide support 8, handles 171 are employed hinged to the head 109 and having enlargements 172 in the form of cams. It is clear that, if the locking handles are turned upwards so as to unlock the head 109 from the base 8 of the guide-support, the head 109 is lifted from the base 8 owing to the enlargements 172, thereby facilitating the dismantling of the mounting.

What I claim is:-

1. In a machine-gun, a firing device with 90 a firing lever, a safety device to hinder the loading of the machine-gun when said firing device is in firing position, comprising a safety lever adapted to rotate about an axis behind the loading channel, resilient means for connecting said safety lever and said firing lever, and permitting of operating said firing device when the safety lever is prevented to enter the loading channel.

2. In a machine-gun, a firing device with 100

a firing lever, a safety device to hinder the loading of the machine-gun when said firing device is in firing position, comprising a safety lever adapted to rotate about an axis behind the loading channel, a link connecting the safety lever to the firing lever, this link comprising two parts, a socket pivoted to the safety lever, a rod pivoted to the firing lever, a spring inserted between the socket and the rod.

3. In a machine-gun, a firing device comprising a support hinged on the head of the mounting and resting on the support of said head, a foot rest and a firing pedal mounted on a slide, means for fixing the position of the slide along the support, a fire-cam acting on the fire-lever, means to transmit the motion from the firing pedal to the fire-cam, safety means to hinder the loading of the machine-gun when the firing pedal is depressed.

4. In a machine-gun, a firing device comprising a support hinged on the head of the mounting and resting on the support of said head, a foot rest and a firing pedal mounted on a slide, means for fixing the position of the slide along the support, a fire-cam acting on the fire-lever, means to transmit the motion from the firing pedal to the fire-cam, a safety device to hinder the loading of the machine-gun when said firing pedal is depressed comprising a safety lever rotating about an axis behind the loading channel, a link connecting the safety lever and the fire lever, this link comprising two parts, a socket pivoted on the safety lever, a rod pivoted to the firing lever, a spring inserted between the socket and the rod.

In testimony whereof I have affixed my signature.

AUGUSTE LOUIS RICORDEL.
